PHOTOTUBE

Herbert Nelson, East Orange, N. J., assignor to
 Radio Corporation of America, a corporation
 of Delaware

Application September 19, 1933, Serial No. 690,045

4 Claims. (Cl. 250—41.5)

This invention relates to space discharge devices which respond to light, and more particularly such devices in which photoelectric currents control the magnitude of a thermionic discharge.

Phototubes as usually made are in most of their practical applications used in conjunction with a vacuum tube amplifier. A high resistance must be used in the external circuit of the photoelectrodes to obtain from the small photoelectric current sufficient voltage drop in the resistance to affect the bias of the grid of the amplifier to which the phototube is coupled, and the high impedance of the phototube causes difficulty in making an efficient coupling between the phototube and the amplifier.

To simplify the problem of amplifying a photoelectric current use has been made of a combination tube comprising a phototube and a vacuum tube amplifier mounted in one bulb, with the photocathode connected to the control grid of the amplifier, and the photoanode connected to the anode of the amplifier, but this combination tube has not been particularly successful commercially. The structural arrangement is complicated, some kind of shielding arrangement between phototube and amplifier is necessary, and a vacuum type phototube must be used because the thermionic amplifier is of the vacuum type.

One object of the present invention is to provide a method of photoelectrically controlling the output of a thermionic cathode in a novel way whereby a greater output is obtained at lower voltages than by the methods heretofore available.

Another object is to provide a phototube in which the output of a thermionic cathode is controlled by a photocathode in a simple and direct way and without the aid of a control grid or of high external resistance.

A further object is to provide a phototube in which the current flow from a thermionic cathode in the same bulb as a photoelectrode is controlled by the effects produced in the atmosphere of the bulb by the photoelectric current.

Still another object is to provide a high output phototube having a very simple and strong electrode assembly.

In accordance with my invention amplification of the photoelectric current is obtained by means of a thermionic cathode such as a straight filament, a light sensitive photocathode adjacent the thermionic cathode, and a grid-like electrode interposed between the two cath-

odes and surrounding the filament, and acting as a common anode for both cathodes. These three electrodes are mounted in a tube containing argon or similar gas at a pressure of 100 to 125 microns such as is commonly used in gas type phototubes.

In operation the three electrodes are maintained at different potentials so chosen that the difference of potential between the grid anode and the thermionic cathode is less than the ionization potential of the gas, but the potential difference between the anode and the photocathode is greater than the ionization potential. Under such conditions a small change in the emission of the photocathode causes a large change in the thermionic current to the anode. It is my belief that when the tube is in operation and as long as the photocathode is dark, the current from the thermionic cathode to the anode is substantially free from ionization and is space charge limited. When light falls on the tube a photocurrent flows from the photocathode to the anode and ionizes the gas to an extent dependent on the magnitude of the photocurrent. Most of the ions appear near the anode where the speed of the photoelectrons is highest, and hence are in the vicinity of the thermionic cathode. The positive ions partially neutralize the space charge adjacent the thermionic cathode, and as a result the thermionic current increases, and in effect a large amplification of the photocurrent is obtained.

The invention will be better understood by reference to the following specification when considered in connection with the accompanying drawing in which:

Figure 1 is a perspective view of one form of tube made in accordance with my invention, parts being broken away better to show internal structure;

Figure 2 is a perspective view of a modification of the tube, parts being broken away better to show internal structure;

Figures 3 and 4 are circuit diagrams of practical applications of the tube;

Figure 5 is a curve showing the relation between photoelectric and thermionic currents in the tube.

The particular form of tube shown in Figure 1 has a cylindrical electrode assembly comprising a thermionic cathode 1, preferably a V shaped filament coated with oxides, such as barium and strontium oxides. The cathode emission is not critical, but should be sufficient to cause the current to be limited by space charge. The co-

operating tubular electrode 2, which is coaxial with and surrounds the thermionic cathode, operates as an anode, and is conveniently constructed like the usual grid consisting of a helix wound on two side rods, so that electrons may pass through it. This grid electrode 2 may be either flat or cylindrical, and the diameter and turns per inch of the wire wound on the side rods may be selected to give the tube the desired electrical characteristics. The grid-like or perforated anode 2 is surrounded by a tubular photocathode 3, which is coaxial with the anode 2 and which may also be flat or cylindrical. The photocathode 3 may be made light sensitive on its outer surface in well known ways, and I have obtained good results with the process generally used to make thin film caesium oxide photocathodes. I prefer to make the photocathode of silver coated sheet metal, and to permit operation of the tube independent of the direction of the incident light. I may perforate the photocathode with a plurality of openings 4. These openings 4 in the photocathode should be large enough so that the electrostatic field in the opening will not prevent electrons emitted from the outer surface of the photocathode passing through the opening to the anode 2. The filamentary thermionic cathode 1 is carried on leads 5 and 6, the anode 2 on leads 7 and 8, and the photocathode 3 on leads 9 and 10, all these electrode leads being carried by the stem 11 which is sealed into the neck of a cylindrical bulb 12. The tubes should contain enough gas to produce appreciable ionization at reasonable operating voltages, such as 90 to 100 volts. Good results have been obtained with tubes, made as shown in Figure 1, which contained argon at the usual pressure of gas type phototubes such as 100 to 125 microns.

The tube of Figure 1 is satisfactory for practical purposes, but for exceptionally accurate measurements the tube may be modified, as shown in Figure 2, to embody precautions to prevent the light from the filament affecting the photocathode. The tube shown in Figure 2 has a filament 13, of straight fine wire, such as nickel, coated with barium and strontium oxides. The upper end of the filament 13 is connected to a wire 14, and both filament 13 and the wire 14 are supported by lead wires 15 and 16. A cylindrical grid electrode or anode 17 having metal end collars 18 and 19 is mounted to surround and be coaxial with the cathode 13, and is supported by a lead wire 20 welded to the lower end collar 19. A flat photocathode 21, of solid sheet metal with its surface rendered light sensitive, is set edgewise to the filament 13, which lies in the plane of the flat photocathode 21. The only part of the photocathode exposed to the light from the filament 13 is the edge 22. Additional shielding of even the edge 22 of the photocathode may be obtained by a thin narrow metal strip 23 mounted on the metal collars 18 and 19 to lie in alignment with the filament 13 and to be out of contact with the wire coil or helix of the grid electrode or anode 17. This narrow strip shades or shields the photocathode 21 from the incandescent filament 13. In a tube thus constructed the photocathode 21 is affected only by light which is intentionally projected upon its surface to operate the tube. The photocathode 21 is carried by a lead wire 24, and the lead wires for all electrodes are supported by the glass stem 25, which is sealed into the neck of the glass bulb 26 which encloses the entire electrode

assembly. This tube operates in essentially the same way as the tube shown in Figure 1.

Tubes constructed as shown in Figures 1 and 2 have enough output to operate a relay when connected as shown in Figures 3 and 4, in which the tube elements are represented diagrammatically. In Figure 3 the filamentary thermionic cathode 27 is heated by a 1.5 volt filament battery 28, the perforated anode 29 is kept about 6 volts positive with reference to the cathode 27 by the 6 volt plate battery 30, and the photocathode 31 is made negative with reference to both the filamentary cathode 27 and the anode 29 by the 45 volt battery 32, which has its positive terminal connected to the filament 27 and also to the negative pole of the anode battery 30. With no light on the photocathode 31 of the tube connected as shown in Figure 3, there is no photoelectric current in the tube, but a thermionic discharge, too small to operate the relay 33, flows between the filamentary cathode 27 and the anode 29. As the voltage drop of about 6 volts between the cathode 27 and the anode 29 is less than the ionization potential of the gas in the tube, the discharge between them is free from ionization and is limited by space charge.

When light falls upon the light sensitive cathode 31 photoelectrons are emitted by it and travel toward the anode 29 and the thermionic cathode 27, both of which are positive with reference to the photocathode. The voltage drop between the photocathode and the anode 29, due to the two batteries 30 and 32, is greater than the ionizing potential of the gas in the tube, hence the photoelectrons flowing to the anode 29 and filament 27 ionize the gas and thus produce positive ions. The number of positive ions thus produced is dependent on the number of photoelectrons emitted by the photocathode, and these positive ions neutralize to an extent dependent on their number the electron space charge between the filament 27 and the anode 29. A comparatively small photoelectron current from the photocathode 31 will produce enough ions to have a marked effect on the space charge and thereby cause a comparatively large thermionic current to flow from the filament 27 to the anode 29 whereupon the relay 33 operates and the work circuit 34 is closed.

Figure 4 illustrates an adaptation to a picture transmission, television, or other like circuit of a phototube embodying my invention and operating as explained in connection with Figure 3. The circuit of Figure 4 differs from that of Figure 3, in that, the 15 volt plate battery 35 is of a higher potential than the plate battery 30 in Figure 3, and that the relay 33 in the anode circuit is replaced by a coupling transformer with its primary 36 in the anode circuit and its secondary 37 connected to the first tube of a thermionic amplifier. The output impedance of my photoamplifier tube is comparatively low, hence the impedance of the transformer is correspondingly low, and need not necessarily be higher than 2000 ohms. Such a low impedance transformer is much less expensive and much less susceptible to electrical disturbances such as "pick-up" from power lines or the like than the high impedance transformer necessarily used with the usual phototube.

Figure 5 shows a curve 38 obtained from one tube made in accordance with this invention and showing the change produced in the thermionic current flowing between the thermionic cathode and anode in response to a change in the photo-

electric current due to variation in the intensity of the light falling on the photocathode. In this tube a photoelectric current of one microampere corresponds to a thermionic current of approximately three milliamperes, as shown by the dotted line 39, and an increase in photoelectric current to three microamperes causes the therimionic current to increase to 4.2 milliamperes, as shown by the dotted line 40. The amplification of the photoelectric current is so great that in many cases my tube will replace the usual combination of a phototube and glow tube, or phototube and external amplifier, and will produce much the same results by a simpler and less expensive device.

It is to be understood that the embodiments of the invention hereinbefore described are merely illustrative and that many changes may be made without departing from the scope of the invention which is limited only by the appended claims.

What is claimed is:

1. A photoelectric current amplifier comprising a sealed glass envelope containing gas at reduced pressure and enclosing a thermionic cathode, an anode, and a photocathode external to said cathode and anode, an output circuit between said thermionic cathode and said anode which includes means for impressing upon said anode a potential which is positive relative to said thermionic cathode and less than the ionizing potential of the gas, and means for maintaining between said anode and said photocathode a constant difference of potential greater than the ionizing potential of the gas.

2. Means for amplifying electric currents comprising a sealed glass envelope containing gas at reduced pressure and enclosing a thermionic

cathode, a source of electrons, and an anode common to both said cathode and said source, means for maintaining between said anode and said source a constant difference of potential greater than the ionizing potential of the gas, 5 means for maintaining between said anode and said thermionic cathode a constant difference of potential less than the ionizing potential of the gas, and an output circuit between said thermionic cathode and said anode. 10

3. A photoelectric current amplifier comprising a sealed glass envelope containing gas at reduced pressure and enclosing a thermionic cathode, a photocathode, and an anode mounted to cooperate with both said cathodes, an output 15 circuit between said anode and said thermionic cathode, means for maintaining both said anode and said thermionic cathode positive with reference to said photocathode at potentials such that the potential of said anode to said photocathode is greater and to said thermionic cathode is less than the ionizing potential of the gas. 20

4. Means for amplifying photoelectric currents comprising a sealed glass envelope containing gas at reduced pressure and enclosing 25 a thermionic cathode, a photocathode, and an anode common to both said cathodes, an input circuit including said photocathode and said anode, an output circuit including said thermionic cathode and said anode, and a source 30 of potential greater than the ionizing potential of the gas with its negative terminal connected to said photocathode, an intermediate point at a positive potential lower than the ionizing potential of the gas connected to said thermionic cathode, and its positive terminal connected to said anode. 35
